UNITED STATES PATENT OFFICE

KARL F. JORSS, OF WASHINGTON, DISTRICT OF COLUMBIA, ASSIGNOR TO CRITTALL CASEMENT WINDOW COMPANY, OF DETROIT, MICHIGAN, A CORPORATION OF MICHIGAN

CASEMENT WINDOW

Application filed May 3, 1930. Serial No. 449,615.

The invention relates to certain improvements in a combined casement window and channel frame screen fixed to the casement frame and has for its object the application 5 of a latch to the casement frame and the keeper therefor on the sash and adapted to enter the channel of the screen frame, the latter being provided with a slot adjacent the keeper in which the dog of the latch operates 10 and which is substantially closed by the dog in all positions of the latter.

The invention is illustrated in the accompanying drawings, in which:—

Fig. 1 is a fragmentary horizontal section 15 of a casement window involving the novel construction.

Fig. 2 is a fragmentary front elevation, partly in section.

Fig. 3 is a section on line 3—3 of Fig. 2. 20 In metal casement windows, it is frequently desired to have the screen frame fixed to the inner face of the casement frame, but such an arrangement has proven more or less unsatisfactory, because of the necessity of 25 passing certain elements of the latching mechanism through openings in the wire mesh fabric of the screen, which involves difficulties in keeping the opening closed and in preventing damage to the screen fabric. 30 The present invention is designed particularly to provide an effective latch which does not pass through any portion of the mesh fabric of the screen, but which is provided with a specially shaped bolt or dog member, 35 which operates through a slot in the screen frame and effectively closes the slot to the ingress of insects in all positions of the latch.

In the drawings, 1 indicates the metal frame of a casement window of standard construction with which cooperates the metal sash 2, which may be pivoted at one side or at the top of the frame and is adapted to be swung outwardly, when the window is to be opened by the usual mechanism provided for 45 opening and closing the sash.

Fixed to the inner face of the casement frame 1 is a screen having a sheet metal frame 3 of channel form in which the wire mesh fabric 3' is secured in any appropriate manner, the opening of the channel frame of the

screen being directed toward the sash or the outside of the window, but the screen, as a whole, lying wholly inside of the sash.

Mounted on a face plate 4, which is bolted or otherwise secured to the inside of the frame 1, is a latch comprising a pivot stud 5, a handle 6 and a bolt or dog, such as 7, which latter is of substantially sector shape having an arcuate outer edge concentric with the pivotal axis of the handle. 60

Fixed to the inner face of the frame of the sash 2 is a slotted keeper 8 adapted to be engaged by the bolt or dog 7 of the latch, when the window is locked, one inner face of the slot in the keeper being beveled, so that the engagement of the latch and dog therewith will draw the sash to a tight seat against the frame. The keeper 8, when the sash is closed, projects within the channel of the screen frame in the manner and form 70 shown in Figs. 1 and 3 and said screen frame on the side adjacent the latch and in substantial alignment with the keeper is provided with a slot 9 in which the dog or bolt 7 of the keeper operates and which is practically 75 closed by the dog in all positions of the latch, the two extreme positions of the dog in locking and unlocking positions being indicated in full and dotted lines in Fig. 2. This arrangement obviates the general objection to 80 making openings in the mesh fabric of the screen and nevertheless provides an effective latch which may be operated at all times without uncovering any opening through which insects may enter, inasmuch as the only 85 opening in the screen structure is that in the side thereof between the latch and the keeper, which opening, as stated, is substantially closed or filled at all times by the dog 7. 90

What I claim is:

1. In a combined casement window and channel frame screen fixed to the casement frame, a latch pivoted to the casement frame, and a keeper fixed to the sash frame and projecting into the screen frame, said screen frame having a slot therein through which the dog of the latch operates, said dog having a form to substantially close the slot in all positions of the latch. 95

2. In a combined casement window and 100

channel frame screen fixed to the casement frame, a latch pivoted to the casement frame having a substantially sector-shaped dog, and a keeper on the sash frame projecting into the channel of the screen frame, the screen frame having a slot therein through which the dog operates and which is substantially closed by the dog in all positions of the latch.

In testimony whereof I affix my signature.
